US00D596823S

(12) **United States Design Patent**
Thurm

(10) **Patent No.:** **US D596,823 S**
(45) **Date of Patent:** **** Jul. 21, 2009**

(54) **MOTORCYCLE LIFT**

(76) Inventor: **Kenneth R. Thurm**, 2348 N. Rockridge Cir., Orange, CA (US) 92867

(**) Term: **14 Years**

(21) Appl. No.: **29/312,196**

(22) Filed: **Oct. 3, 2008**

(51) **LOC (9) Cl.** **12-05**

(52) **U.S. Cl.** **D34/28**

(58) **Field of Classification Search** **D34/28, D34/31, 33; D12/101, 406, 408; 280/410, 280/402; 254/2 C, 8 R, 10 R, 45, 124, 88; 414/539, 540, 541, 678, 921**

See application file for complete search history.

(57) **CLAIM**

The ornamental design for a motorcycle lift, as shown and described.

DESCRIPTION

FIG. 1 is a top perspective view of the motorcycle lift of the present invention showing my new design;

FIG. 2 is a top plan view thereof;

FIG. 3 is a right side elevational view thereof;

FIG. 4 is a bottom plan view thereof;

FIG. 5 is a rear end elevational view thereof;

FIG. 6 is a front end elevational view thereof; and,

FIG. 7 is a perspective view of the motorcycle lift of the present invention depicted in a stowed (i.e., lowered) configuration.
